CARBURETOR WITH CHOKE CONTROL

Arthur R. Baker, Indianapolis, Ind., assignor to
Columbia Carburetor Company, Washington,
D. C., a corporation of Delaware

Application March 20, 1933, Serial No. 661,809
Renewed July 29, 1935

6 Claims. (Cl. 261—64)

This invention relates to carburetors and is an improvement on the carburetor shown in my Patent No. 1,877,117, granted September 13, 1932.

An object of the invention is to provide a carburetor adapted for use with low grade blended fuel such for example as a gasoline having a high end point which under normal conditions is unsatisfactory for use in engines having a high compression ratio and further to provide a carburetor which will reduce excessive detonation when operating with low grade fuel.

A further object is to provide a carburetor having a combination of automatic choke and accelerating valve which valve is operated in response to varying load demands upon the engine.

A further general object is to simplify the construction and to increase the efficiency of carburetors in general and more particularly carburetors such as that shown in the patent referred to.

Referring to the accompanying drawings, which are made a part hereof and on which similar reference characters indicate similar parts,

Figure 1 is a plan view of the carburetor with a portion in section to show a motor fuel jet,

Figure 2, a section on line 2—2 of Figure 1,

Figure 3, a section on line 3—3 of Figure 1,

Figure 4, a detail showing mechanism for operating the throttle valve,

Figure 5, a sectional view of a modified form of fuel jet,

Figure 6, a view on line 6—6 of Figure 2 looking downward as indicated by the arrows,

Figure 7, a view on line 7—7 of Figure 2 looking upward as indicated by the arrows,

Figure 8, a section on line 8—8 of Figure 6,

Figure 9, a section on line 9—9 of Figure 6, and

Figure 10, a section on line 10—10 of Figure 6.

In the drawings, casing elements 10 and 11 are removably secured together in any suitable way. A fuel well 12 is formed in the lower casing element 10 and motor fuel overflows into the well 12 from a fuel pan 9. Fuel is delivered into the pan through a port 13 to which is connected a fuel conduit from the tank which may be located at some remote place on the vehicle. Flow of fuel into the pan 9 is controlled by a float 14 which is pivotally attached at 15 to a screw 16 which is threaded through the casing 11. A portion 18 of the upper casing encloses a chamber 17 which forms an intake chamber through which the fuel passes into the engine. The casing 18 is flanged at 19 which flange is drilled at 20 to receive bolts, not shown, by means of which the

carburetor may be attached to the side of the engine. An expansion chamber 21 is formed in the upper casing 11 and forms what may be regarded as a chamber continuous with the well 12. In order to secure the best operating results the carburetor should be mounted on the engine with the side of the carburetor which contains the well 12 preferably positioned toward the front of the vehicle. With the well 12 so positioned the float 14 will have a tendency to remain lower and thus to open the inlet port 13 to permit a more free flow of fuel into the well. The purpose of this arrangement is that when the car is climbing a hill and is in an inclined position, the float will be at a lower level and this will insure a full flow of gasoline into the pan. This is as it should be; for in climbing a hill the engine makes greater demands for fuel than when on the level, or when descending a hill and it is necessary therefore to provide for this free flow of fuel. When descending a hill the car is tilted into the other direction. There is less demand for a rich fuel at this time and since the float rises it retards the flow of fuel into the pan and thus insures a leaner mixture at a time when a lean mixture is sufficient for operating the engine. Positioning of the carburetor therefore, as indicated, enables an operator to economize on fuel.

A tube or pipe 22 is positioned in the well 12 extending to a point near the bottom of the well. The upper end of this tube connects with a chamber 23 with which chamber an annular passage 24 connects. This annular passage is between a needle valve stem 25 and a tube 5 having an enlarged end which is threaded into a bore in the carburetor casing. The valve stem 25 has a tapered end 26 which controls a valve 27 through which motor fuel is sprayed into a hot cap 34 positioned in the exhaust manifold 35. An air intake pipe 28, having a ball check valve 90, is secured in the casing 11 and extends down into a tube 29. This tube has ports 31 at its lower end which communicate with a body of liquid fluid in the well 12. A cup 32 is fitted in the lower end of the tube 29 and into this cup extends the lower end of the tube 28. The tube 28 is slotted at 30 as shown and this slot extends up above the normal level of the fuel in the pan 9. A tube 33 is fitted within the tube 29 and spaced from the sides of the tube 28. Air is sucked down through the tube 28 and passes out the end of this tube and up around the outside of the tube and the inside of the cup and on up into the space between the tube 28 and the tube 33. The rising air acts to lift fuel which enters through the ports 31 and 35

carries it up into the pan 9. The air therefore acts as a pump to lift the fuel into the pan. During this course, the air takes up an appreciable amount of lighter fuel elements so that when the air leaves the space 21 above the fuel it is partially laden with vaporized fuel. The liquid drops of the fuel, however, which may have been carried up with the rising stream of air, fall back into the well 12. There will be something of a churning up of the fuel in the pumping operation just described which will assist the air in taking on a partial load of vaporized fuel elements.

A port 8 communicates with the space 21 through which the fuel laden air passes to a space 6 between the tube 5 and the tube 7. The tube 7 is threaded into the carburetor casing. The hot cap 34 also has an enlarged inner end which is screw threaded into the same bore of the casing. Air drawn through the annular space 6 passes out around the end of the tube 5 and acts to draw fuel through the space 24. The fuel and air are mixed in the hot cap 34 and also are here heated by the hot gases passing out through the exhaust manifold 35. A valve stem 25 is screw threaded at 36 into a screw cap 37. The screw cap 37 is threaded into a cap 38 at 39. The threads 36 and 39 have a different pitch so the rotation of the screw cap 37 will move the valve stem 25 endwise. Instead of having the threads of a different pitch of course it would be possible to have one set of threads right hand and the other left hand to effect the adjustment. The valve stem also carries a disk 49 to which is secured one end of a flexible diaphragm or bellows 41 which acts to seal the chamber 23 to prevent leakage of fuel elements out past the screw threads 39 and 36. The sleeve 1 is surrounded by a spiral 42 through which the fuel mixture from the hot cap 34 travels to a port 43 through which it passes to an axial bore 44 and out through radial bores 45 and a space 46 from which it passes into the chamber 17. A sleeve 50 in conjunction with a conical surface 49 on the end of a cap 48 forms a Venturi opening 47 through which air passes into the chamber 17. The velocity of the air through the Venturi opening 47 is sufficiently high to suck fuel gases through the opening 46 and to thoroughly mix all elements of the fuel charge as they enter into the intake chamber 17. Any liquid fuel elements which may condense about the casing into which the element 48 is threaded may drip back through a port 51 where they are sucked up and vaporized by the stream of vaporized fuel passing out through the radial bores 45. The Venturi sleeve 50 has a pin 52 which carries a roller 53. This roller operates in a slot 57 in the casing 10 and in an arcuate slot in an operating cam arm 54. The cam arm 54 is pivotally supported on the carburetor casing on an eccentric 55 which is operated by a lever 56. Movement of the lever 56 by virtue of the eccentric 55 will adjust the arm 54 vertically. This adjusts the Venturi sleeve as a whole to vary the opening at 47 to determine the idling opening of the venturi. The cam arm 54 is operated by means of a lever 86 which is attached thereto at 58. When the link 86 is pushed toward the right the cam arm 54 will swing in a counter-clockwise direction on its eccentric support and the curved slot in the cam arm 54 will move the roller 53 vertically carrying the Venturi sleeve 50 upward. The first movement of the cam arm 54 will impart a rapid upward movement to the sleeve. The movement of the sleeve relative to movement of the cam arm 54 will decrease as the sleeve approaches its uppermost position. When

the arm 54 has reached the dotted line position shown in Figure 4 movement of the link 86 will cause a very slight movement of the Venturi sleeve. When returning from the closed position the open movement will first be very slow and then will gradually increase as the cam arm approaches the position shown in full lines in Figure 4. The cap 48 may also be given a slight vertical adjustment after it has been screwed to position. This adjustment is made by means of a key member 80 having a ball 81 through which extends a pin 82. The pin engages a slot 83 in the upper end of the cap 48. The key member 80 is provided with a packing ring 85 to prevent leakage of fuel elements out past the walls of the tube 15 enclosing it. The upper end of the opening is closed by a screw cap 84. When it is desired to adjust the cap 48 the cap 84 is removed and the key member 80 rotated by a screw driver or similar tool to rotate the cap member 48, the pawl and slot 20 connection 81, 82 and 83 serving as a universal joint. A tube 59 extends through the walls of the air inlet 92. This tube communicates with atmosphere through a port 60. A port 61 forms communication between the fuel pan 9 and the interior of the tube 59. This port is normally closed by a valve 62 which is held against the valve seat by means of a spring 63. A flange portion 64 extends into the path of the lower edge of the Venturi sleeve 50 when this sleeve is depressed. When the lower end of the sleeve engages the disk 64 further downward movement of the Venturi sleeve will depress the valve 62. This permits fuel to pass through the port 61 into the tube 59 where it is mixed with air drawn in through the port 60. The fuel charge is delivered into the inlet air stream of the engine. The upper end of the valve 62 is tapered as shown at 91 so that the amount of fuel delivered through the port 61 increases as the valve is further depressed.

The structure just described operates to supply the additional fuel necessary as the throttle is opened beyond a predetermined extent.

Among the features of the present carburetor are the means for maintaining the fuel charge 45 with the correct proportions of fuel and air. Insofar as possible these correct proportions are automatically maintained in response to the demands of the engine under increased load, increased speed, or accelerating conditions. 50 Means about to be described provide automatic control of the fuel charge to meet these conditions. The usual butterfly valve 66 is mounted on a shaft 67 in the intake barrel 92 through which air is delivered to the engine. The shaft 55 67 is off center of the butterfly valve as shown best in Figure 9. The shaft 67 has secured thereon an arm carrying a pin 68 which engages the side of a slotted arm 69 which is loosely mounted on the shaft 67. A spring 79 on the shaft 67 tends to urge the shaft 67 in a direction to keep the pin 68 in engagement with the lower side of the arm 69. A plunger 70 is pivoted to the slotted end of the arm 69 and this plunger has an enlarged end 71 against which seats one end 65 of a spring 72 which surrounds the plunger. The other end of this spring engages a stop 73 positioned within a sleeve 74 and secured therein in any suitable way not shown. A spring 75 surrounds the sleeve 74 and bears against a 70 flange portion 76. A packing cup 80 is secured to the flange portion 76 to provide a seal to prevent leakage between the flange and the walls of an enclosing cylinder 77. A tiny air port 78 communicates with a chamber back of the pack- 75

ing cup 80. Normally the butterfly valve 66 is in the position shown in Figure 9. This is also the position during idling of the engine. When the engine is first started or when it is accelerated from the idling position there is a strong suction through the tube 92. The first effect of this suction is to draw in an additional supply of fuel through the tube 59 to enrich the fuel charge. This enrichment will occur before the butterfly valve 66 is materially moved from the position shown in Figure 9. Suction, however, through the tube 92 will swing the butterfly valve 66 in a clockwise direction against the tension of spring 72. But for the vacuum at the back of the cup 80 the sleeve 74 will also be moved to the right. This movement, however, cannot occur quickly due to the vacuum. A strong suction would be necessary to maintain the butterfly valve in an open position but for the fact that as soon as it moves to this position, the sleeve 74 tends to move, the flanged end 76 being limited in its movement by the rate with which air may be drawn in through the port 78. As soon as the sleeve 74 has moved to its extreme limit to the right the tension on spring 72 is released so that the valve 66 will remain in its open position and may be maintained in this position by suction which is only sufficient to compress the spring 75. The tension of spring 72 will be so determined as to give the proper fuel mixture at the starting and at the accelerating speed and the spring 75 may be made only with sufficient tension to restore the suction cup to its extreme left position when the throttle has been closed or the engine stopped.

In case of engine back-fire the butterfly valve may yield and swing counterclockwise, the spring 79 restoring it to closed position after the back-fire. The butterfly valve by yielding as indicated prevents any injury as a result of the back-fire.

In the modified form of spray nozzle shown in Figure 5 the valve 87 is made to slide within the bore 88 in a Venturi sleeve 89. This has a neat fit within the Venturi sleeve so as to completely cut off the supply of fuel and may be so adjusted as to regulate the supply within any predetermined limits.

In operation air which is partly saturated with lighter fuel is drawn through the port 8 and through the annular spaces surrounding the tube 5. This suction at the end of the tube creates a strong suction through the chamber 23, and thus sucks a charge of motor fuel up through the tube 22. The air which is already partially saturated with motor fuel is mixed with a relatively large volume of atomized motor fuel in the hot cap 34. At this point of mixing the mixture is heated to a relatively high temperature by the exhaust gases passing through the exhaust manifold 35. In the process of heating this mixture of gases to a high temperature some non-condensable gases are formed. Tests have shown that among these gases are carbon monoxide and hydrogen which gases play an important role in subsequent reactions in the engine. The mixture of gases in the cap 34 is too rich to fire. This rich mixture is passed through the spiral passage around the side of the hot cap and passes through bore 43 into bore 44 out through ports 45 and passage 46 into the chamber 17. This rich mixture of gases is mixed with a relatively large volume of cold air which comes in through the Venturi sleeve 92 and which strikes the sloping portions 49 and 75 is deflected radially outwardly against the walls

of the venturi, creating a strong aspirating action on the rich mixture issuing through the passage 46. The volume of air admitted to the mixture is controlled, of course, by the operator by means of the link 86 which is manually operated. When the Venturi throttle is opened to a predetermined extent it is necessary to supply an additional quantity of motor fuel. This is effected by means of the valve 62. As the Venturi throttle engages the disk 64 it depresses this disk as the throttle is further opened. This permits the raw motor fuel to flow from the receptacle 9 into the tube 59 where it passes into the Venturi opening along with air which is drawn in through the port 60.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:—

1. In a carburetor having a butterfly valve, means for operating said valve in response to load demands of the engine comprising means for creating a suction on the butterfly valve so as to open said valve slightly after starting of the engine, and means for maintaining said butterfly valve in an open position so long as the engine is operated at normal speed and under a normal load and means for minimizing the amount of suction required to maintain the valve in open position at operating load after the engine has come up to full operating speed, substantially as set forth.

2. The combination with the air intake to a carburetor, of a butterfly valve, said valve being pivotally mounted off center, resilient means for holding said valve to close off said air intake, means yielding under suction to permit said butterfly valve to open to permit air to flow to the said carburetor, and means for relieving said tension on said butterfly valve whereby the valve may be maintained in an open position with relatively light suction through the said air intake to maintain a proper proportion of air and fuel during normal operation of the engine, substantially as set forth.

3. In a carburetor of the kind described, a Venturi throttle valve, means for operating said Venturi throttle valve comprising a cam element, a pivotal support for said cam element, means for adjusting said support vertically to adjust the idling opening of the throttle, a cam slot, a lug on said venturi engageable in said slot, means for pivotally swinging said cam to raise and lower the said Venturi throttle, first movement of said cam from open position toward closed position causing relatively rapid movement of the venturi, said rapid movement gradually decreasing to a very slow movement as the throttle approaches a closed position, substantially as set forth.

4. In a carburetor having an inlet for air and an inlet for fuel, means for mixing said air and fuel and thereafter adding a large volume of air thereto comprising a Venturi forming sleeve, means for adjusting the air supplying ports comprising an adjustable cap, a threaded stem on said cap, and means engageable with said stem for rotating it to adjust the said cap relative to said sleeve, substantially as set forth.

5. In a carburetor having an air controlling

- valve, means for operating said valve in response to load demands of the engine comprising means for creating a suction on said valve so as to open it a little after starting of the engine, means for maintaining said valve in open position so long as the engine is operated at normal speed and under normal load, and means for minimizing the amount of suction required to maintain the valve in open position at operating load after the engine has come up to full operating speed.
6. The combination with the air intake to a carburetor, of an air controlling valve, a pair of

springs for holding said valve in closed position, and yielding under suction to permit said valve to open to permit air to flow to the said carburetor and means for relieving the tension of one of said springs to reduce the pressure tending to close said valve whereby the valve may be maintained in open position with light suction through the air intake to maintain a proper proportion of air and fuel during normal operation of the engine.
